HATCH CONSTRUCTION

Charles David Bonsall, Pittsburgh, Pa., assignor
to P. H. Murphy Company, New Kensington,
Pa., a corporation of Pennsylvania

Application February 8, 1935, Serial No. 5,621

14 Claims. (Cl. 108—5)

My invention relates to the hatchway construction of a refrigerator car. Its principal object is to devise a construction wherein the hatch opening is provided with a metal lining which cooperates with upturned flanges of the roof sheet to constitute a support for the upper hopper member and wherein the danger of leakage at their connection is eliminated. The invention consists in the parts and in the combinations and arrangements of parts hereinafter described and claimed.

In the accompanying drawings, which form part of this specification, and wherein like symbols refer to like parts wherever they occur,

Fig. 1 is a plan view of the end portion of a refrigerator car embodying my invention,

Fig. 2 is a vertical partial cross-section thereof on the line 2—2 of Fig. 1,

Fig. 3 is a vertical partial longitudinal section 20 on the line 3—3 of Fig. 1,

Fig. 4 is a detail view through the hinge of the hatch cover on the line 4—4 of Fig. 1,

Fig. 5 is an enlarged view of a portion of the hatch sheet blank showing the form of the hole 25 punched therein preparatory to bending up the side flanges thereof to form the hatch hole,

Fig. 6 is a detail view of the round corner piece,

Fig. 7 is a detail view showing the hatch sheet 30 with hatch hole flanges turned up and with one round corner open and another round corner closed with a corner piece,

Fig. 8 is a detail vertical sectional view through the body of the hatch sheet and showing in elevation, the corner piece welded to the side flange 35 and to the body of said hatch sheet, and

Figs. 9, 10 and 11 are views similar to Fig. 3, 40 illustrating three modified forms of hatch construction.

The car roof illustrated in the accompanying drawings comprises sheets 1 that span from side plate 2 to side plate 2 of the car and have their ends rigidly secured to such side plates. The side margins of the sheets have upstanding flanges 3 and these flanges are straddled by seam caps 4, which are secured to said flanges and to the side plates of the car, as by rivets 5.

The car is provided with suitable insulation 6. In the construction illustrated, there are metal subcarlines 7 which are supported by the 50 side plates of the car. Upon these subcarlines are supported wood fillers 8 whose upper surface has a pitch conforming to the pitch of the roof. Suitable insulating lining 9 is suspended from the subcarlines.

The endmost roof sheet, hereinafter referred

to as the hatch sheet, has one or two hatchways which lead into the ice bunker of the car. The hatchway opening is defined by a framework, which, in the construction illustrated in Figs. 2 and 3, comprises metal angle-shaped carline members 10 that extend from side plate to side plate with their ends rigidly secured thereto and themselves supporting longitudinally disposed angle members 11 secured to and flush with the tops of said carline members by means of angle 10 brackets 12 riveted or otherwise fastened to said angle members and said carline members respectively. Opposite the lower part of the hatchways are metal subcarlines 13 of angular section with their ends secured to brackets 14 fixed to 15 the side plates.

According to the present invention, each hatchway has a sheet metal lining 15 that constitutes an upward extension of the lining of the bunker that is common to the two hatchways. 20 Each hatch lining 15 extends upwardly above the general level of the roof sheet and downwardly below the level of the insulating ceiling lining 9 of the car. The bottom margin of the hatch lining 15 is riveted or welded to a downwardly 25 flanged metal flashing member 17 secured to the insulating ceiling lining 9. The top margin of the hatch liner 15 is secured to an upstanding flange 18 provided therefor on the hatch sheet along the margin of the hatchway opening. In 30 the construction illustrated in Figs. 2 and 3, there is a hopper member 19 which is located inside of the liner 15 and extends from a point above the top of the sheet flange 18 downwardly below the main surface of the roof. The portion of the 35 hopper member 19 below the main surface of the roof has its sides converging to constitute a seat for a wooden plug 20 of the type commonly used. The top end of the hatch lining 15 is substantially 40 flush with the top edge of the upstanding flange 18 around the margin of the opening in the hatch sheet, and the liner, sheet flange and hopper are secured together by rivets, welds or otherwise. I prefer to secure them together by means of a weld 21 of metal added continuously 45 on the top edges of the liner 15 and the sheet flange 18 and against the body of the hopper 19. I prefer also to make the liner 15 and the hopper member 19 of stainless steel and to make the weld 21 also of stainless steel. The upper margin of 50 the hopper member is pressed to form a flange 22 that extends laterally outwardly and thence downwardly to reinforce said member and afford suitable support for the ice in the course of loading.

According to my invention, the hatchway opening is made with rounded corners. For this purpose, the hole 23 cut in the hatch sheet is of the shape of a rectangle with quadrantal or 5 segmental extensions 23a at its respective corners (see Fig. 5). The sides of the rectangular portion of such hole are bent up along lines that connect the ends of the corner arcs to which they are substantially tangential, thus forming side 10 flanges 24; this arrangement leaves a gap at each corner between the ends of adjacent side flanges 24 and each of these gaps is closed by a small oblong piece 25 of sheet metal bent conformably to the curve of the rounded corner of the hole 15 and soldered or welded to the body and flanges of the hatch sheet to form the upstanding flange 18.

A suitable door or cover 26 is provided for the hatch, which cover is preferably hinged to a suitable part of the roof structure. In the construction illustrated, each hatch cover has two T-shaped strap hinges 27, their long strap leaves being secured to the hatch cover and the shorter and wider leaves being riveted or welded to the 25 side of the upstanding roof seam.

The construction illustrated in Fig. 9 is similar to that shown in Fig. 3 except that the angle bars 10a and 11a that define the hatchway opening are of oblique angle section arranged with their 30 sides converging downwardly and the lining 15a is formed with downwardly converging sides that rest flatwise against inclined sides of the hatchway frame thus formed. In this construction, the hatchway sheet rests on the horizontal 35 flanges of the hatchway frame and the hopper member 19a rests against the converging portion of the liner, which, in turn, receives support from the converging sides of said frame.

In the construction illustrated in Fig. 10, the 40 hopper member 19b is wholly above the general level of the roof sheets and the converging seat for the wooden plug is formed by making the lining 15b with converging sides that rest against the converging flanges of the hatchway frame.

45 The modification illustrated in Fig. 11 has the upper or hopper member 19c entirely above the general level of the roof sheets with its lower end positioned outside of the sheet flange 18 and secured thereto by rivets or welds as in the other cases. In this modification, the upper or hopper member 19c flares upwardly and serves as a seat for the wooden plug, such seat being in this case located considerably higher than in the other cases described above.

55 The hatch construction hereinbefore described has several advantages. In the first place, the sheet metal lining takes the place of the thick planks or boards heretofore used for the side walls of the hatchway and which greatly reduces 60 the effective width and length of the hatch opening. Likewise, the use of the metal liner in connection with the flanging of the roof sheet affords a very substantial support for riveting or welding the hopper member, especially when the roof 65 sheet is supported by the rigid frame around the hatch opening. Again, by making the liner of stainless steel or like metal that is not affected by brine and ordinary acids, corrosion is avoided and the effective life of the hatchway increased. 70 Again, the riveting or welding of the liner and hopper to the hatch sheet avoids the danger of leakage into the space occupied by the insulating material. Making the hole in the hatch sheet round-cornered, with the curved corner pieces 75 welded thereon, is a simple operation and enables

the hopper to be easily made by die-pressing with a desirable hopper shape and with a top flange that greatly increases the strength thereof, facilitates the sliding of the ice over it and is well adapted to receive the hatch cover.

What I claim is:

1. In a hatchway construction, a sheet having a hole therein and an upstanding flange around said hole, a metal liner whose upper end portion is opposite said flange, a hopper member having a portion opposite said flange and means for securing together the flange and the portions of the liner and the hopper member opposite said flange. 15

2. A refrigerator car comprising side plates, a roof thereon, and a hatchway extending through the roof, a metal framework around the hatchway opening and supported by said side plates, the marginal portion of the roof around said opening being supported by said frame and having an upstanding flange, a lining member for said opening extending upwardly opposite said flange and an upper member having a portion opposite said flange, said members and flange being secured together and the member which is innermost below said flange having downwardly converging sides. 20

3. A refrigerator car construction comprising a metal roof, an ice bunker and a hatchway extending through the roof to said bunker, the hatchway construction comprising a metal lining extending above the body portion of the roof and a metal hopper member which extends through the roof and has downwardly converging sides below the roof, said roof having an upwardly extending flange around the hatchway opening, and a weld uniting the upper edges of said flange and lining with said hopper member. 25

4. A refrigerator car construction comprising a metal roof, an ice bunker and a hatchway extending through the roof to said bunker, the hatchway construction comprising a metal lining extending above the body portion of the roof and a metal hopper member which extends through the roof and has downwardly converging sides below the roof, and means for securing said hopper member, lining and roof together. 40

5. A refrigerator car comprising side plates, a roof thereon, an ice bunker, a hatchway extending through the roof into the bunker, a metal framework supported by said side plates and defining the hatchway opening, the inner sides of said framework inclining inwardly and downwardly, and a lining for said hatchway having a portion resting flatwise against the inclined portion of said framework. 50

6. A refrigerator car comprising a roof, a substructure, an ice bunker, a hatchway extending through the roof into the bunker, a framework of obtuse angled metal members supported by said substructure and defining the hatchway opening, said members being disposed with one flange extending laterally outwardly from the other flange and said other flange inclining downwardly and inwardly, and a lining for said hatchway having a portion resting flatwise against the inclined portions of said framework members. 60

7. A refrigerator car comprising side plates, a roof thereon, an ice bunker, and a hatchway extending through the roof into the bunker, a framework of metal members of obtuse-angled section supported by said side plates and defining the hatchway opening, said members being arranged with one flange inclining inwardly and 70

75

downwardly, and a plug seat member having a portion resting flatwise against the inclined portion of said framework.

8. A refrigerator car comprising side plates, a roof thereon, a hatchway extending through the roof, a metal framework supported by said side plates and defining the hatchway opening, the outer sides of said framework inclining inwardly and downwardly, a lining for said hatchway having a portion resting flatwise against the inclined portion of said framework, and a hopper member having a lower portion inside said lining and conforming to the inclined portion thereof and an upper portion extending above the roof.
- 15 9. In a hatchway construction, a roof sheet having a round cornered parallel sided hole therein and an integral upstanding flange along the straight edges of said hole, and curved corner pieces of metal welded to the body of said sheet and the ends of said flanges in continuation thereof, a metal liner whose upper end fits in said flange, and a pressed metal hopper having a portion opposite the top portion of said liner, and means for securing said flange, liner and hopper together.
- 20 10. A refrigerator car construction comprising a metal roof, and a hatchway extending through the roof, the hatchway construction comprising a metal lining extending above the body portion of the roof and an upper member having a portion lapping the upper margin of said lining, and said roof having an upstanding flange opposite and secured to the lapped portions of said lining and upper member.

11. A refrigerator car construction comprising a roof of metal sheets, an ice bunker and a hatchway extending through a roof sheet to said bunker, the hatchway construction comprising a metal lining extending above the body portion of said roof sheet and an upper member whose lower portion laps the upper margin of said lining, and said roof sheet having an upstanding flange opposite and secured to the lapped portions of said lining and upper member.

10 12. In a hatchway construction, a roof sheet having a hole therein and an upstanding flange around said hole, a liner of stainless steel whose upper end fits in said flange, and a hopper of stainless steel having a portion opposite the top portion of said liner, and means for securing said flange, liner and hopper together.

15 13. A refrigerator car having a metal roof with upstanding seams, an ice bunker, a hatchway extending through said roof into said bunker, a cover for said hatchway and hinges securing said cover to one of said seams.

20 14. A refrigerator car comprising a roof of metal sheets, one of which has a round cornered hatch hole with upstanding flanges, an ice bunker 25 and a hatchway extending through said hatch hole to said bunker, the hatchway construction comprising a metal lining whose upper portion is opposite said flanges and a hopper member having a portion opposite said flanges, and means 30 for securing said hopper member to said flanges and to the portion of the lining opposite thereto.

CHARLES DAVID BONSALL.
